[57] CLAIM

The ornamental design for a fluid pressure cylinder for a conveyor belt, as shown.

DESCRIPTION

FIG. 1 is a top plan view of a fluid pressure cylinder for a conveyor belt showing our new design;

FIG. 2 is a front view thereof;

FIG. 3 is a right side view thereof;

FIG. 4 is a left side view thereof;

FIG. 5 is a bottom view thereof;

FIG. 6 is a perspective view thereof;

FIG. 7 is a cross-sectional view along 7—7 of FIG. 2 thereof; and,

FIG. 8 is a cross-sectional view along 8—8 of FIG. 1 thereof.
